UNITED STATES PATENT OFFICE

WILLIAM H. WINTER, OF BOYDEN, IOWA

AUTOMATIC OSCILLATING WINDSTACKER HOOD

Application filed February 24, 1930. Serial No. 430,648.

The object of my invention is to provide an automatic oscillating windstacker hood which is simple, durable and comparatively inexpensive to manufacture.

More particularly, it is the object of my invention to provide an automatic oscillating means for the hood of a windstacker of a threshing machine so that a continuous oscillating motion can be imparted to the hood for directing the straw angularly toward and away from the machine.

A further object is to provide a hood oscillating mechanism consisting of a yoke member pivoted to the windstacker and coactable with a cam or other means for imparting oscillating motion to the hood of the windstacker.

Still another object is to provide adjusting means so that either the degree of oscillating travel of the hood or the position of such travel may be changed as desired.

Another object is to provide means for rendering the device inoperable when it is desired to stop the oscillation of the hood.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of a windstacker showing my hood oscillating mechanism applied thereto.

Figure 2 is a side elevation of the same.

Figure 3 is a perspective view of a yoke member included in the mechanism of the device.

Figure 4 is a perspective view of a lever.

Figure 5 is a perspective view of a cam and

Figure 6 is an enlarged detailed sectional view on the line 6—6 of Figure 2 showing a pivotal connection for portions of the device.

On the accompanying drawings I have used the reference numeral 10 to indicate generally the housing of a threshing machine. A windstacker blower housing is indicated at 12, a windstacker at 14 and a hood at 16. The windstacker 14 usually consists

of a telescopic elbow 14a, a primary tube 14b and a secondary tube 14c telescopically mounted with respect to the tube 14b. The hood 16 usually consists of a plurality of sections 16a, 16b and 16c telescopically arranged in the form of an elbow. The sections 16a, 16b and 16c are pivoted at 18 and a spring 20 is provided for constraining them toward extended position.

A ring gear 22 of the worm type is mounted on the windstacker 14 and coacts with a worm 24. The worm 24 is mounted on a shaft 26 which extends into a gear housing 28. A drive shaft 30 also extends into the gear housing 28 and is operatively connected therein with the shaft 26 for imparting a plurality of revolutions thereto, first in one direction and then in another for oscillating the windstacker 14 on a vertical axis.

The drive shaft 30 is provided with a pulley 32 which is belted by a belt 34 to any rotating shaft of the threshing machine 10. On the drawings it is illustrated as extending to a pulley 36 on the windstacker blower shaft.

The windstacker 14 is pivoted at 38 and the outer end may be manually adjusted as to height by means of a hand wheel 40 operating a worm geared drum 42 on which a cable 44 is wound. In connection with a compensating bar 48 mounted on the section 14b of the windstacker 14, a pivotally mounted adjusting handle 50 is provided. This handle may be swung to various positions and locked relative to a sector 52.

A rope 54 extends from the lever 50 around a pulley 56 on the outer end of the compensating bar 48, over a pulley 58 on the section 14c of the windstacker 14 and is ordinarily connected with a bracket 60 on the hood 16 of the windstacker. The foregoing construction refers to the ordinary type of threshing machine at present in extensive use. I will now describe my particular invention as applied to such a windstacker.

My invention includes a semi-circular yoke member 62 having inclined arms 64 adapted to be pivotally connected with the lower end of the elbow 14a of the windstacker 14. In Figure 6 I have illustrated a pivotal connec-

tion in which a bolt 66 extends through the elbow 14a and a spacer 68 is secured thereon by a nut 70. Washers 72 are provided for reinforcement purposes and a washer 74 serves 5 as a flange.

One of the arms 64 of the yoke member 62 is pivoted on a reduced portion of the spacer 68. A sector member 76 is riveted as at 78 to the arm 64 and is likewise pivoted on the reduced portion of the spacer 68. A lever 80 is also pivoted on this reduced portion. The other arm 64 is pivoted on a similar spacer having a shorter reduced portion as there are no other parts pivoted on such reduced portion 15 (see Figure 1).

The lever 80 is provided with a lug 82 fitting over the edge of the sector 76 to resist a set screw 84 which may be tightened after the lever 80 has been adjusted as desired with 20 respect to the sector 76. The rope 54 in my installation extends over a pulley 86 on the bracket 60, over guide pulleys 88 and terminates in a hook 90 which is selectively coactable with any one of a plurality of openings 92 formed in the lever 80. An opening 25 94 in the yoke 62 is also provided for the hook 90, the purpose of which will hereinafter be fully described.

In connection with the yoke member 62 I 30 provide a cam 96 adapted to be secured to the shaft 26 and to coact with the yoke member 62 as the shaft 26 rotates whereby the yoke member 62 may be raised and lowered at each revolution of the shaft 26 in either direction.

35

Practical operation

In the operation of my device, assuming the parts to be in the position shown in Figure 40 2, it will be obvious that a half revolution of the shaft 26 will rotate the cam 96 and allow the spring 20 to pull the section 16c of the hood 16 to the dotted line position for blowing straw in the direction of the arrow 98. When the cam 96 again assumes the position 45 illustrated, the straw will be blown in the direction of the arrow 100. Thus as the shaft 26 continues to rotate, the hood 16 will be automatically oscillated once each revolution of the shaft.

50 When it is desired to decrease the degree of oscillation, the hook 90 can be hooked in an opening 92 of the lever 80 closer to the pivot bolt 66. When it is desired to alter the position of oscillating travel of the hood 16 55 without altering the throw thereof, the set screw 84 may be loosened, the lever 80 moved pivotally as desired and the screw 84 again tightened. The adjusting device 50-52 is ordinarily provided for merely changing the 60 position of the hood 16 when my oscillating device is not used but it is desirable to retain it on the machine so that it can still be used for adjusting the hood when it is not desired to automatically oscillate the hood.

65 I have provided a means for stopping the

oscillation of the hood 16 and at the same time maintaining the yoke member 62 in a position where the cam 96 does not coact therewith. This means consists of hooking the hook 90 in the opening 94 whereupon the 70 spring 20 will maintain the yoke member 62 in its raised position whereby the cam 96 will not coact with it. The adjusting device 50-52 may then be used for setting the hood 16 where desired.

75 The purpose of the inclined arms 64 is so that when the windstacker 14 is swung a half revolution from the position shown on the drawings for the purpose of moving the threshing machine from one job to another, the semi-circular member 62 will cease to coact with the cam 96 as it will be on the opposite side of the vertical axis of the windstacker. Then when the windstacker is again brought into stacking position, the inclined arms will cause the yoke member 62 to be raised onto the cam 96 for proper coaction therewith.

80 The yoke member 62 being semi-circular makes it possible for proper coaction with the cam 96 during the oscillating movement of the windstacker 14 on its vertical axis. This movement of course is imparted to it automatically from the shaft 26 as before described. It will be found that by the use 85 of my device, a better straw stack can be formed as the straw is distributed over a wider area and packs better without the tendency to topple over as when the hood 16 is set in one position.

90 Some changes such as the substitution of other driving means instead of the cam 96 may be made in my device and other mechanically equivalent parts may be substituted instead of those shown on the drawings 95 without departing from the real spirit and purpose of my invention, and it is my intention to cover by my claims, any modified forms of structure or use of mechanical equivalents, which may be reasonably included within their scope.

100 I claim as my invention:

1. For use with an oscillatable windstacker having an oscillatable hood and mechanism for oscillating said windstacker including a shaft, a mechanism for automatically oscillating said hood comprising a semi-circular yoke pivoted to said windstacker, a cam on said shaft for coaction with said yoke and an operative connection between said yoke and said hood.

115 2. For use with an oscillatable windstacker having an oscillatable hood and mechanism for oscillating said windstacker including a shaft, a mechanism for automatically oscillating said hood comprising a semi-circular yoke pivoted to said windstacker, a cam on said shaft for coaction with said yoke and an operative connection between said yoke and said hood, said op- 120

125

130

erative connection comprising a lever pivoted to the yoke, means for locking it in any position to which it may be pivoted and a connecting member between the lever and the hood.

3. For use with an oscillatable windstacker having an oscillatable hood and mechanism for oscillating said windstacker including a shaft, a mechanism for automatically oscillating said hood comprising a semi-circular oscillatable yoke pivoted to said windstacker, means on said shaft for coaction with said yoke whereby to oscillate the yoke as the shaft rotates regardless of the position of the yoke relative to said means and an operative connection between said yoke and said hood.

Des Moines, Iowa, February 6, 1930.
